(57) **CLAIM**

The ornamental design for a bottle stopper, as shown and described.

DESCRIPTION

FIG. 1 is a front perspective view of a bottle stopper according to the present design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is an exploded front perspective view of the bottle stopper of FIG. 1 shown with the O-rings removed and relocated below the stopper for clarity of disclosure.

The broken lines are shown for the purpose of illustrating parts of the article that form no part of the claimed design.

1 Claim, 7 Drawing Sheets
